H. M. STEPHENSON

ELECTRIC ILLUMINATION OF SEWING MACHINES OR THE LIKE

Filed April 2, 1927

Fig. 1.

Fig. 2.

Inventor:
Hugh M. Stephenson,
by *William S. Jones*
His Attorney.

UNITED STATES PATENT OFFICE.

HUGH M. STEPHENSON, OF FORT WAYNE, INDIANA, ASSIGNOR TO GENERAL ELECTRIC COMPANY, A CORPORATION OF NEW YORK.

ELECTRIC ILLUMINATION OF SEWING MACHINES OR THE LIKE.

Application filed April 2, 1927. Serial No. 180,575.

My invention relates to the electric illumination of sewing-machines or other similar machines. In the arrangements heretofore used for such illumination, the lamp has been 5 improperly placed for the best lighting of the material to be sewn and the position of the lamp was such that there was a great likelihood of bending the reflector or breaking the lamp.

10 In accordance with my invention, the lamp is placed near the material to be worked upon so that the beam of light shines directly thereon without any shadows from intervening objects. Furthermore, it is so placed that 15 it cannot be struck and thereby broken. To this end, I mount an electric lamp socket within a recess in the head of the sewing or other machine, the light rays from the electric lamp in the socket shining on the material to be worked upon, so that there is no shadow cast by the operating mechanism on the material to be sewn at the point where it passes beneath the needle position. The 20 needle is also illuminated so that it can be 25 threaded readily.

Other features of novelty which characterize my invention are pointed out with particularity in the claims annexed to and forming a part of this specification. For a better 30 understanding of my invention, reference may be had to the following description taken in connection with the accompanying drawing, in which Fig. 1 is a side elevation of a sewing machine embodying my invention, 35 and Fig. 2 is a front elevation, with parts broken away, of the sewing machine of Fig. 1.

Referring to the drawing, 1 is a cloth plate or bed of a sewing machine. Rising from the bed 1 at one end thereof is the usual 40 low arm comprising the vertical member 2, horizontal member 3 and head 4. The head 4 is at the end of the arm and has mounted therein for reciprocation a usual needle bar 5 and a presser-bar 6. The needle bar carries 45 the needle 7, and the presser-bar, the presser-foot 8. The needle bar is reciprocated by the usual mechanism within the arm, whereby stitches in the material are taken by the needle 7 and thread 9, coacting with the bobbin and 50 thread thereon (not shown).

In order to throw a beam of light on that portion of the cloth plate on which the material to be sewn or worked upon is placed and also on the needle 7 so that it can be threaded, 55 an electric lamp 10 is placed in a recess of

substantially the same size throughout its length formed in the lower structure of the head 4. This lamp is mounted in a lighting socket 11. The head has an aperture 12 formed in the bottom thereof through which the beam of light is directed, the filament of the lamp being so positioned with respect to the aperture that the light from the filament will be directed by the edge of the aperture on a relatively small area directly below the 60 needle bar 5. The aperture is in front of the needle bar 5, that is, when considered from the operator's position when operating the machine. Consider Fig. 1 in this regard; the operator faces the machine as illustrated and the lamp is placed in front of the needle bar, and the presser-bar is in back of the needle bar. In Fig. 2, the operator faces the machine from the right hand side of this figure and we have the same relation of parts. The 65 head has a recess 13 in substantial alignment with the aperture 12, the socket 11 fitting in this recess. This socket may be adjusted in the recess toward and away from the aperture, the lamp 10 remaining lighted, whereby the 70 area illuminated is considerably varied to suit the operator. The lamp is shown in the lowest position in Fig. 2 and the area illuminated is indicated by the dot and dash lines. In Fig. 1, the lamp is shown in its uppermost 75 lighted position and the area illuminated is also indicated by the dot and dash lines. In order to move the socket 11 in the recess 13, a member 14 is fastened to the rear of the socket. This member is shown as being L 80 shaped, the horizontal portion of the L having a slot tightly engaging a slot in the insulation 15 at the rear of the socket in order that the socket can not be disengaged without considerable effort. To prevent the socket 85 from turning, the slot in the member 14 and the slot in the insulation 15 have square corners. The vertical portion of the L is engaged by a screw 16 which extends through a slot 17 in the head 4. By loosening the screw, the 90 L shaped member carrying the socket 11 and lamp 10 may be moved and by tightening up the screw again these parts may be clamped 95 in any desired position permitted by the length of the slot 17.

The portion of the socket 11 engaged by the lamp 10 is made of metal, the lamp having a bayonet connection therewith. In the lighted position of the lamp, the socket 11 is 100 in good electrical contact with the sides of 110

recess 13. In order to supply electric current to the lamp, a source of electric current is shown as a transformer 18 supplied by leads 19. The transformer may be conveniently located beneath the cloth plate 1 and fastened thereto. One side 20 of the secondary of the transformer is grounded to the head 4 through the arm of the machine. The other side 21 of the transformer is carried by means of a conductor 22 through the hollow arm of the machine to a spring contact 23 in the socket 11. This contact 23 is engaged by a contact on the lamp 10. It will thus be seen that the circuit for the lamp is completed when the socket is in contact with the sides of the recess. In order to turn the light out, the screw 16 is loosened and the socket and lamp are moved into their uppermost position, whereupon the socket is moved out of contact with the sides of the recess 13, due to the cutting away or jog 24 in the wall of the head 4. When the socket and lamp are in their uppermost positions, the socket is completely withdrawn from the recess, but the bulb of the lamp 10 centers the socket 11 for re-entry into the recess 13, as the bulb of the lamp is substantially the same diameter as the recess 13 and the socket 11.

In order to assemble the socket 11 and member 14 in place in the head, the socket is inserted in the slot in the L shaped member; the face plate 25 is removed from the head 4, the member 14 carrying the socket 11 is inserted in position through the opening which is normally covered by the face plate, the screw 16 is then screwed into the member 14, and the face plate placed back into its proper position. The lamp is placed in the socket after the socket is placed in the head 4, the member 14 and the socket 10 being removed to its lowest position.

By using the transformer 18 or any other source of low potential, the lamp 10 may be of the type used in flash lights or automobiles of say 3 to 6 volts. Such lamps are very rugged and will readily stand any vibration of the sewing machine without injury. Furthermore, the use of a low voltage lamp permits the running of a single wire to the lamp, the other side of the circuit being grounded, without any danger of an electrical shock to the operator.

I have shown and described a novel arrangement for the control of the electric circuit of the lamp, but it may be controlled in any usual way.

I desire it to be understood that many modifications may be made in the arrangement shown and described, and I aim in the appended claims to cover all modifications which do not depart from the spirit and scope of my invention.

What I claim as new and desire to secure by Letters Patent of the United States, is:

65 1. In a sewing machine or the like, a head,

a needle bar mounted in said head, and means for directing a beam of light on the material to be worked upon comprising an aperture formed in the bottom of said head, and an electric lamp within said head with its filament so positioned with respect to said aperture that the light from said filament will be directed by the edge of said aperture on a relatively small area directly below the needle bar.

2. In a sewing machine or the like, a head, a needle bar mounted in said head, and means for directing a beam of light on the material to be worked upon comprising an aperture formed in the bottom of said head, an electric lamp within said head with its filament so positioned with respect to said aperture that the light from said filament will be directed by the edge of said aperture on a relatively small area directly below the needle bar, and means for adjusting said lamp toward and away from said aperture to vary the area illuminated.

3. In a sewing machine or the like, a head, a needle bar mounted in said head, and means for directing a beam of light on the material to be worked upon comprising an aperture formed in the bottom of said head in front of said needle bar, an electric lamp within said head with its filament so positioned with respect to said aperture that the light from said filament will be directed by the edge of said aperture on a relatively small area directly below the needle bar, and means for adjusting said lamp toward and away from said aperture to vary the area illuminated.

4. In a sewing machine or the like, a head, and means for directing a beam of light on the material to be worked upon comprising an aperture formed in the bottom of said head, a lighting socket contained within said head for the reception of an electric lamp, and means for adjusting said socket toward and away from said aperture in order to vary the area illuminated.

5. In a sewing machine or the like, a head, a needle bar mounted in said head, and means for directing a beam of light on the material to be worked upon comprising an aperture formed in the bottom of said head in front of said needle bar, said head having a recess in substantial alignment with said aperture, a lighting socket fitting in said recess, said socket being arranged for the reception of an electric lamp, and means for adjusting said socket toward and away from said aperture in order to vary the area illuminated.

6. In a sewing machine or the like, a head, means for directing a beam of light on the material to be worked upon comprising an aperture formed in the bottom of said head, a source of electric current having one side grounded to said head, said head having a recess in substantial alignment with said aperture, a lighting socket fitting in said recess,

- the other side of said source of electric current being connected to said socket, said socket being arranged for the reception of an electric lamp, the circuit of said lamp being completed when said socket is in contact with the sides of said recess, and means for moving said socket out of contact with the sides of said recess whereby the circuit of said lamp is opened.
7. In a sewing machine or the like, a head, a needle bar mounted in said head, means for directing a beam of light on the material to be worked upon comprising an aperture formed in the bottom of said head in front of said needle bar, a source of electric current having one side grounded to said head, said head having a recess in substantial alignment with said aperture, a lighting socket fitting in said recess, the other side of said source of electric current being connected to said socket, said socket being arranged for the reception of an electric lamp, the circuit of said lamp being completed when said socket is in contact with the sides of said recess, and means for moving said socket out of contact with the sides of said recess whereby the circuit of said lamp is opened.
8. In a sewing machine or the like, a head, a needle bar mounted in said head, means for directing a beam of light on the material to be worked upon comprising an aperture formed in the bottom of said head in front of said needle bar, a source of electric current having one side grounded to said head, said head having a recess in substantial alignment with said aperture, a lighting socket fitting in said recess, the other side of said source of electric current being connected to said socket, said socket being arranged for the reception of an electric lamp, the circuit of said lamp being completed when said socket is in contact with the sides of said recess, and means for adjusting said socket toward and away from said aperture to vary the area illuminated and for moving said socket out of contact with the sides of said recess whereby the circuit of said lamp is opened.

said aperture to vary the area illuminated and for moving said socket out of contact with the sides of said recess whereby the circuit of said lamp is opened.

9. In a sewing machine or the like, a head, a needle bar mounted in said head, means for directing a beam of light on the material to be worked upon comprising an aperture formed in the bottom of said head in front of said needle bar, a source of electric current having one side grounded to said head, said head having a recess in substantial alignment with said aperture, a lighting socket fitting in said recess, the other side of said source of electric current being connected to said socket, said socket being arranged for the reception of an electric lamp, the circuit of said lamp being completed when said socket is in contact with the sides of said recess, and means for adjusting said socket toward and away from said aperture to vary the area illuminated and for moving said socket out of contact with the sides of said recess whereby the circuit of said lamp is opened.

10. In a sewing machine or the like, a head, a needle bar mounted in said head, said head having a recess in the lower structure thereof, an electric lamp mounted in said recess with its filament so positioned that the light from said filament will be directed on a relatively small area directly below the needle bar, and means for adjusting the position of said lamp to vary the area illuminated.

In witness whereof, I have hereunto set my hand this 30th day of March, 1927.

HUGH M. STEPHENSON.
